JOHN W. FITZ GERALD, OF SHOREWOOD, WISCONSIN, ASSIGNOR TO BRIGGS & STRATTON CORPORATION, OF MILWAUKEE, WISCONSIN, A CORPORATION OF WISCONSIN

CURRENT-SUPPLY DEVICE

Application filed October 27, 1926. Serial No. 144,409.

This invention relates to new and useful improvements in means and circuit arrangement whereby a source of current, such as is ordinarily used for lighting purposes, may be utilized to supply the necessary current for operating a radio receiver.

An object of this invention resides in the provision of an improved and simplified battery-eliminator and circuit arrangement therefor wherein current for the radio receiver is obtained directly from the service lines through a current adapting means connected with the radio receiver by suitable conductors across which is floated an electrolytic cell having electro-chemical energy storing characteristics in the circuit of which is incorporated means for ironing or smoothing out the current impulses whereby current supplied the receiver from the service line is in a substantially straight line to thus eliminate the reproduction of a hum or other audible noise.

It is a characteristic of a condenser used with a rectifier wherein current is directed into the electrolytic cell during the one-half of the wave period only and is exhausted therefrom during the other half that during the charging period, the electrolytic cell voltage increases and likewise during the other half period its voltage decreases, consequently, the current furnished to the receiver increases and decreases thus causing an audible noise or hum in the receiver, and this invention has as another object the eliminating of this variation in the current and, consequently, the elimination of the resulting hum in the radio receiver by the imposition of a choke coil in the circuit between the electrolytic cell and receiver.

It is also a characteristic of a choke coil to tend to hold back or choke sudden increases in current due to an increase in voltage and to hold back or retard a decrease in current due to a sudden drop in voltage, and this invention contemplates the provision of means for further assisting the choking action of the coil by the inductance or generation of an additional current to tend to hold the resultant current at a constant value for supplying the radio receiver.

A more specific object of this invention resides in the provision of a battery eliminator of the character described having an improved choke coil included in the receiver circuit between the electrolytic cell and the receiver and having windings supplied with current of different characteristics.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

The single view is a diagrammatic illustration of the apparatus and circuit embodying my invention.

The circuit illustrated in the accompanying drawing is adapted to be used in connection with alternating current and the numerals 5 and 6 designate alternating current service lines such as the 110-volt circuit ordinarily used for lighting purposes in residences, and are connected, as at 7 and 8, with the movable contacts 9 and 10, respectively, of a relay 11 adapted to be operated to engage stationary contacts 12 and 13, respectively, upon energization of a core 14 of a choke coil 15, to be later described. The stationary contacts 12 and 13 are electrically connected with the primary winding 16 of a transformer 17 by conductors 18 and 19, respectively, and inductively associated with the primary winding 16 is a secondary winding 20.

One end 21 of the secondary winding is connected with one side of the filament 22 of a rectifying bulb 23 by a conductor 24, the other side of the filament being connected with the secondary winding at an intermediate point 25 by a conductor 26. The other

end 27 of the secondary winding is connected with the positive side of the filament circuit 28 of a radio receiver, diagrammatically illustrated as 29, by a conductor 30, the negative side 31 of the receiver filament circuit being connected with one side 32 of a filament switch 33 the other side 34 of which is connected with the plate 35 of the rectifying bulb through a conductor 36, a winding 37 wound about the armature 14 of the choke coil 15, and a conductor 38.

Floated across the conductors 30 and 38 is an electrolytic cell 39 having electro-chemical energy storing characteristics so that, assuming that the relay 11 is closed, the current flowing through the primary winding 16 induces or generates in the secondary winding 20, a current of the proper value to light the filament 22 and generate the arc necessary to rectify the current. The rectified current flows through the choke coil winding 37, through the filament circuit of the receiver and back through the conductor 30. Assuming, for the purpose of illustration, the receiver demands two amperes, and the rectifier passes four amperes during its charging period, the excess of current enters the electrolytic condenser to charge the same, which charge is given up by the condenser during the period no current passes the rectifier to fill in the void in the current and maintain a flow of current to the receiver at all times.

However, as the voltage of the electrolytic cell fluctuates in value due to the intermittent action of the rectifier, the current supplied to the radio receiver is in a series of pulsations. The choke winding 37, however, tends to iron or smooth out the impulses and, if desired, means may be provided to assist the winding 37 to further wipe out irregularities remaining in the circuit so that the current flowing to the radio receiver has a substantially constant value.

In Figure 1, I have illustrated one manner of overcoming the fluctuations in the value of the current which is in the form of a winding 40 wound around the core 14 and preferably of light wire and of proportionately many more turns than the winding 37 so that its current requirement is considerably under that of the heavy winding 37. The winding 40 is connectible with a source of energy and in the embodiment illustrated, one end of the winding 40 is connected across the terminals of the transformer secondary winding 20 and has a variable resistor 41 incorporated in its circuit to control the amount of current furnished to the winding 40.

The current in the winding 40 is of such value that as the current increases in the winding 37, the current likewise increases in the winding 40 and endeavors to induce or generate a current in opposition to the current in the winding 37 and of a value

sufficient to pull the current therein down to a constant value. Likewise, when the current flowing through the winding 37 decreases, the current in the winding 40 tends to induce a current in the winding 37 having the characteristic of raising or increasing the current therein and thereby maintaining a substantially constant current value. Thus it will be seen that the light winding 40 further stabilizes the value of the current supplied the radio receiver and prevents the reproduction of a hum or other noise in the receiver.

With the construction illustrated, the conductors 5 and 6 are in constant electrical connection with the alternating current service line, not shown, and closing of the radio receiver filament circuit switch 33 connects the winding 37 across the electrolytic cell, energizing the winding which magnetizes core 14. Immediately upon the magnetizing of the core 14, relay 11 closes to engage the movable contacts 9 and 10 with the stationary contacts 12 and 13, respectively, connecting the primary winding of the transformer with the service line to set the device in operation.

Likewise, when the switch 33 is open, the continuity of the circuit of the winding 37 is interrupted and, as a result, the relay 11 opens the service line circuit rendering the entire device inoperative.

What I claim as my invention is:

1. In a device for supplying radio receivers with electrical energy from a source of alternating current and including means for rectifying the alternating current, conductors through which the rectified current is supplied the radio receiver and a cell having electro-chemical energy storing characteristics floated across the conductors, the current delivered the receiver tending to flow in pulsating waves having the characteristic of producing an audible hum in the receiver if not eliminated, a choke coil including windings, one connected within one conductor and the other shunted about the secondary of the transformer, whereby pulsations in the current supplied the receiver are ironed out.

2. In a device for supplying radio receivers with electrical energy from a source of alternating current and including means for rectifying the alternating current, conductors through which the rectified current is supplied the radio receiver and an electrolytic cell floated across the conductors, the current delivered to the receiver tending to flow in pulsating waves having the characteristic of producing an audible hum in the receiver if not eliminated, and a choke coil including windings supplied with current of different characteristics, whereby pulsations in the current supplied the receiver are ironed out.

3. In a device for supplying radio receivers with operating energy from a service line and including means for reducing the voltage of the energy from the service line to a predetermined degree, conductors through which current from said means is supplied to the radio receiver, an electrolytic cell floated across the conductors, a core, a winding on the core and connected in one of the conductors, a second winding on the core of light wire and of proportionately many more turns than the first winding, and means shunting the light winding about the secondary of the transformer.

4. In a device for supplying radio receivers with electrical energy from a source of alternating current, and including means for rectifying the alternating current and conductors through which the rectified current is supplied to the radio receiver, a cell having electro-chemical energy storing characteristics floated across the conductors, a choke coil including windings, one connected within one conductor and the other shunted about the secondary of the transformer, and means for controlling the current supplied one winding.

5. In a device for supplying radio receivers with operating energy from a service line and including means for reducing the voltage of the energy from the service line to a predetermined degree, conductors through which current from said means is supplied to the radio receiver, an electrolytic cell floated across the conductors, a winding connected in one of the conductors, a second winding, means connecting the second winding with a source of current, other than that supplied the first coil whereby the current supplied the windings has different characteristics, and means for controlling the current supplied one winding.

6. In a device for supplying radio receivers with operating energy from a service line and including a transformer for reducing the voltage of the energy from the service line to a predetermined degree, conductors through which current from said means is supplied to the radio receiver, an electrolytic cell floated across the conductors, a core, a winding on the core and connected in one of the conductors, a second winding on the core of light wire and of proportionately many more turns than the first winding, means shunting the light winding about the secondary of transformer, and an adjustable control in the circuit of the second winding.

In testimony whereof I hereunto affix my signature.

JOHN W. FITZ GERALD.
